DEVICE FOR USE IN, OR IN CONNECTION WITH, MACHINES FOR SEWING ON BUT- TONS

Vincent Joseph Clarkson, Leeds, England

Application May 22, 1933, Serial No. 672,335
In Great Britain June 6, 1932

8 Claims. (Cl. 112—113)

This invention relates to machines for sewing on buttons, and particularly to means for feeding the buttons in turn to and for correctly positioning them in the clamps or jaws of the machine 5 with their holes in register with the sewing needle or needles.

According to the invention the feeding means comprise shutters or their equivalent adapted to co-operate to first isolate a button from the 10 waiting supply and then transfer it to the carrier for conveying it to the clamps or jaws of the machine.

According to a further feature of the invention the button holding device more particularly 15 though not exclusively for supplying buttons in turn to machines for sewing-on buttons comprises essentially one or more substantially rigid wires or the equivalent on to which the buttons can be threaded one upon another with their 20 holes in register.

In an embodiment of the invention, the buttons are carried by a holder adapted to maintain them in such a position as to bring the holes therein into predetermined positions for the subsequent 25 feeding operation, whereupon a mechanical arm or carrier is advanced up to the button carried by the holder so as to cause one or more fixed pins, spindles, rods or pegs appropriately positioned on said arm or carrier, to come into alignment with one or more of the holes in said button prior to engaging therewith. The feed device provided for supplying buttons successively to the carrier takes the form of shutters or their equivalent adapted to co-operate to first cut off 30 or isolate a button from the waiting supply and then drop or supply it on to the carrier arm. This being effected, the arm or carrier may now be operated automatically to convey the engaged or gripped button into correct position between 35 the jaws or clamps of the sewing-on machine with the holes in the buttons in alignment or register with the sewing needle or needles whereupon the said jaws or clamps close upon the button to hold it in its predetermined position 40 during the operation of sewing-on. In this connection the jaws or clamps in closing upon the positioned button may release the latter from the arm or carrier so as to allow it to perform the next automatic feeding operation. The holder 45 may comprise one or a plurality of substantially rigid wires, rods, pins or the like, whilst at one end (in use, the upper end) of the holder, means are provided whereby it may be suspended from, or otherwise attached to, a support (conveniently 50 55 in the form of an appropriate standard or

bracket) suitably arranged on, or associated with, the machine.

In a preferred embodiment, the holder may comprise parallel legs afforded by two or more substantially rigid wires or the equivalent, or by bending a piece of substantially rigid wire or the equivalent into hairpin formation, the spacing of the legs being such as to permit of buttons being threaded thereon with each leg engaging corresponding holes in the buttons.

In the case of a holder comprising two parallel lengths or legs of wire or the equivalent, the buttons may be retained upon the holder when not required by an appropriate removable stop or stops on said lengths or legs of wire and which 10 may conveniently be in the form of a clip or clips, and in this latter connection said clip or clips 15 may serve to connect the lengths or legs of wire together.

In order that the invention may be clearly 20 understood and readily carried into effect, the same will now be more fully described with reference to the embodiments illustrated by way of example, in the accompanying drawings, in 25

Figure 1 is a part side elevation showing the general arrangement of the main features of the machine viz. the holder, the feed device, and the carrier.

Figures 2, 3 and 4 are respectively a side elevation, plan, and end elevation of a carrier.

Figures 5a, 5b, and 5c are respectively a front elevation, side elevation and a plan of one form of button holder with buttons thereon.

Figures 6, 7 and 8 are a plan, end elevation and front elevation respectively of a feed device.

9a, 9b, and 9c are a plan, front elevation and end elevation respectively of the shutters employed in the feed device.

Figure 10 is a fragmentary sectional elevation 40 showing the guiding of the shutter.

Figure 11 is a diagrammatic plan of the working parts showing, by way of example, a convenient mode of operating them.

Figure 12 is a similar view, showing the parts 45 in the position when the lower pair of shutters are open.

Figure 13 is a similar view showing the parts when the upper pair of shutters are open.

Referring to Figures 5a, 5b, and 5c of the drawings, the holder comprises a pair of parallel legs 1 afforded by bending a piece of wire into hairpin formation, the spacing of the legs being such as to permit their being engaged with or passed 50 through diametrically opposed holes in the but- 55

tons 2 as the latter are threaded thereon by hand or in any other convenient manner. In order to retain the stack or pile of buttons on the holder during transit or when the holder is 5 not in use for supplying buttons say to a button sewing-on machine, a clip such as is shown diagrammatically in Figure 5 at 1a, may be mounted upon the end of one or both the legs of the holder, and in this connection said clip may bridge across 10 and engage both legs.

When in use for supplying buttons to a sewing-on machine, the button holder may be carried by a supporting standard in such a position that the lower end or ends of the wire leg or legs are 5 in register with holes in supply-controlling shutters in conjunction with which works a carrier for conveying the buttons in turn from the holder to the sewing-on position. In this connection no special means should be required for feeding 20 ordinary buttons down the holder beyond the gravity-feed provided by the buttons themselves, but should it be necessary in any case, additional means such as spring-actuated or other loading may be provided to ensure the feeding down of 25 the buttons.

The carrier for transferring the buttons to the sewing-on machine (indicated by dotted lines at Figure 1) comprises a rigid bar 3 provided with a removable plate 4 carrying fixed pins 5 (see Figures 2, 3 and 4), the latter being arranged to correspond exactly with the spacing of the holes in the buttons being used, and consequently with the legs of the holder 1 also.

Figures 6 to 10 inclusive illustrate a convenient 35 device for feeding the buttons 2 singly and successively from the holder to the carrier. The said device consists essentially of upper and lower pairs of shutters 6, 7 adapted to slide apart in guides 8 on the machine frame. Each shutter 40 is recessed so that, when they are closed, holes are afforded at 9, said holes being arranged to correspond with the spacing of the legs of the holder 1 and the holes in the buttons 2.

When the machine is ready for use (see Figure 45 1) the holder 1 with its buttons 2 is carried by a supporting standard 10 in such a position that the lower ends of its legs register with and pass through the holes at 9 in the shutters 6, 7, and also register with the pins 5 on the carrier bar 3. 50 It will be seen that, with this arrangement, a button may be first isolated from the waiting supply and then delivered to the carrier pins 5 by suitable manipulation of the shutters 6, 7. Such manipulation may be effected at the proper 55 time during the travel of the carrier bar 3 to and from the sewing-on machine (Figure 1) by mechanism such as that shown by way of example in Figures 11, 12 and 13, from which it will be seen that the advancing and returning of the 60 carrier bar 3 to and from the sewing needle is effected by a lever 11 pivoted at 11', actuated by engagement with a cam track 12, and engaging the bar 3 through the medium of pin and slot connection 13. The shutters 6, 7 are also actuated by the lever 11 in or about the two extreme 65 stages of its movement, respectively. The lower shutters 7 are actuated when the carrier 3 is beneath them by the co-operation of the lever 11 with an abutment 14 on a spring pressed link 15, 70 movement of which actuates lever and link mechanism 16 to open the lower shutters. The pin and slot 13 between lever 11 and bar 3 affords a lost motion connection at this stage so that the carrier 3 remains stationary with its pins in register with the holes in the buttons while shutters

7 are being opened. The upper shutters 6 are opened when the carrier 3 is at the opposite or forward end of its travel by contact of the lever 11 with the depending end 17' of a T-shaped lever 17 pivoted at 17' on the main plate of the machine. This lever is connected at 17' to one of the shutters directly and to the other through link 18 and lever 18'. The lever 18' is connected to shutter 6 at 18', and pivoted at its other end at 18' to the main plate of the machine. The 10 said upper shutters 6 are normally kept closed by the spring 19 and it will be seen that the actuation of these shutters is such that at all times at least one of them is closed so as to positively hold or guide the lower end or ends 15 of the pin or pins of the holder. Each button is thus transferred to the carrier and positively held with its holes in the required position. Thereafter, the button is picked up by the jaws, clamps, or the like which ultimately support the 20 button for the actual sewing operation.

The feeding device above described and the sewing-on machine are preferably driven synchronously and the jaws which take the button from the carrier 3 and hold it on the work may 25 be conveniently actuated to perform these functions by means of suitable cams and tappets on the feeding machine (not shown) connected to said jaws.

The complete cycle of operations is as follows:—

Assuming that the lowermost button in the holder is resting on the closed jaws of the top shutter, these jaws are caused to open whereby the said button automatically drops on to the 35 (closed) bottom shutter. The two shutters being spaced (vertically) by substantially the overall thickness of a button, the succeeding closure of the top shutter will isolate the button on the bottom shutter from the "stock" in the holder. By 40 suitable timing of the cam or other mechanism, the jaws of the bottom shutter are then opened whereupon the button falls on to the carrier-arm which at this stage is in its extreme rearward 45 position immediately under the holder. The carrier-arm is next advanced to bring the button under the raised and open clamp elements on the sewing-machine, the raising and opening of the clamp elements being effected by mechanism such as levers, and/or cable transmission timed to operate during the forward movement of the carrier-arm. These clamps then automatically close 50 on to the button and, as the carrier-arm returns to its zero position automatically lower the button into position on the work for the actual sewing operation. 55

To adapt the feed device for different sizes or different types of buttons, the shutters and the actual pick-up element of the carrier-arm are adapted for ready removal and replacement by others of the required form to co-operate with the corresponding pin or pins of the holder. Or, and for the same purpose, the shutters and the carrier-arm may be provided with a multiple arrangement of holes or recesses so that the same devices may function with the varied arrangement of pins etc. which the different types of button may necessitate. 60 65

The device is exceedingly simple in operation, 70 foolproof in construction, and efficient in use. With ordinary buttons, no special means is required for feeding the buttons down the holder to the carrier beyond the gravity-feed provided by the buttons themselves. 75

I claim:—

1. In a button sewing machine, means for delivering buttons singly from a stack to the sewing mechanism of the machine, said means comprising a moving carrier bar adapted to travel from a point under the stack to the sewing mechanism, an upper and a lower pair of shutters positioned below said stack and adapted to isolate a single button therebetween and to transfer the same to the bar, and operating means for said shutters, timed to open the lower pair of shutters after the bar reaches the limit of its inward movement toward said point under the stack, and to open the upper pair of shutters at a different point in the cycle of movement of said carrier bar. 5
2. In a button sewing machine, means for delivering buttons singly from a stack to the sewing mechanism of the machine, said means comprising a moving carrier bar adapted to travel from a point under the stack to the sewing mechanism, an upper and a lower pair of shutters positioned below said stack and adapted to isolate a single button therebetween and to transfer the same to the bar, and operating means for said shutters, timed to open the lower pair of shutters after the bar reaches the limit of its inward movement toward said point under the stack, and to open the upper pair of shutters at substantially the end of the outward movement of the bar away from the stack. 10
3. In a button sewing machine, means for delivering buttons singly from a stack to the sewing mechanism of the machine, said means comprising a moving carrier bar adapted to travel from a point under the stack to the sewing mechanism, an upper and a lower pair of shutters positioned below said stack and adapted to isolate a single button therebetween and to transfer the same to the bar, and operating means for said shutters timed to open the lower pair of shutters after the bar reaches the limit of its inward movement toward said point under the stack, and to open the upper pair of shutters during the movement of the bar remote from the stack. 15
4. In a button sewing machine, means for delivering buttons singly from a stack to the sewing mechanism of the machine, said means comprising a reciprocating carrier bar adapted to travel from a position under the stack to the sewing mechanism, two pairs of shutters positioned below said stack and adapted to isolate a single button therebetween and to transfer the same to the bar, said pairs of shutters serving alternately as supporting means for said stack of buttons, means for opening and then closing the upper pair of shutters while the lower pair is closed to isolate a button between said pairs, and means for opening the lower pair while the upper pair is closed and when the feeder bar is positioned thereunder to transfer the isolated button to the bar. 20
5. In a button sewing machine, means for delivering buttons singly from a stack of buttons to the sewing mechanism of the machine, said means comprising a reciprocating feeder bar adapted to travel from a position below the stack to the sewing mechanism, two pairs of shutters 25
- positioned below said stack of buttons and adapted to support the same, said pairs of shutters being normally held in closed position by spring tension means, and means for momentarily opening said pairs of shutters alternately in timed relation to the movement of said feeder bar, to isolate a button from the stack and then drop the same upon the bar when the latter reaches its position under the stack. 30
6. Button holding and delivering means for use with a button sewing machine having a button carrier bar associated therewith, said means comprising a pair of vertically disposed parallel rods supported adjacent their upper ends, and adapted to have a plurality of buttons threaded thereon in stacked formation, two pairs of horizontally disposed shutters adjacent the lower ends of said rods in supporting relation to the stack of buttons, each pair of shutters being opened and closed alternately, first to isolate a button from said stack and then to drop said button to the button carrier bar for the sewing machine, said pairs of shutters each having means for engaging the lower end of each of said rods to position the same accurately, and to prevent lateral displacement thereof. 35
7. Button holding and delivering means for use with a button sewing machine having a button carrier bar associated therewith, said means comprising a pair of vertically disposed parallel rods supported adjacent their upper ends, and adapted to have a plurality of buttons threaded thereon in stacked formation, two pairs of horizontally disposed shutters adjacent the lower ends of said rods in supporting relation to the stack of buttons, each pair of shutters being opened and closed alternately, first to isolate a button from said stack and then to drop said button to the button carrier bar for the sewing machine, said pairs of shutters each having recesses shaped to embrace the lower end of each of said rods to position the same accurately, and to prevent lateral displacement thereof. 40
8. A button carrying device adapted to hold a plurality of buttons in proper relation thereon to be received by a button sewing machine or the like, said device being constructed and arranged to serve as a storing means for the buttons when the device is dis-associated with the machine and as a button feeding means when associated with the machine, said device comprising a single elongated substantially rigid wire bent upon itself intermediate its ends into substantially U-shape, and stop means associated with an end of said wire, the legs formed by the bend therein being disposed in parallel relation to each other and being spaced apart a distance equal to the spacing of the holes in the buttons threaded thereon, the portion of the wire at the bend comprising a means whereby the device may be hung from a support and the buttons retained thereon by said stop means to store said buttons, and whereby said device may thereafter be hung from a support on said machine, and serve as a button feeding magazine for the machine, after the stop means has been rendered inoperative. 45

VINCENT JOSEPH CLARKSON.
